UNDERGROUND SHELTER ENCLOSURE

Raymond Victor Luttrell, Rte. 2, Broken Arrow, Okla.

Filed Jan. 26, 1961, Ser. No. 63,710

Term of patent 3½ years

(Cl. D13—1)

Fig. 2.

I claim:

The ornamental design for an underground shelter enclosure, substantially as shown and described.
